Inventor

John S Peoples

UNITED STATES PATENT OFFICE.

JOHN S. PEOPLES, OF WASHINGTON, DISTRICT OF COLUMBIA, ASSIGNOR TO NEWTON D. BAKER, SECRETARY OF WAR, TRUSTEE.

CARTRIDGE-BELT CONTAINER.

1,406,954.

Specification of Letters Patent. Patented Feb. 14, 1922.

Application filed August 6, 1918. Serial No. 248,645.

To all whom it may concern:

Be it known that I, JOHN S. PEOPLES, captain, Ordnance, N. A., a citizen of the United States, stationed at Washington, District of Columbia, have invented an Improvement in Cartridge-Belt Containers, of which the following is a specification.

The invention described herein may be used by the Government, or any of its officers or employees in prosecution of work for the Government, or by any other person in the United States, without payment of any royalty thereon.

My invention relates to new and useful improvements in cartridge belt containers and has for its object to provide a container that may be quickly and readily attached to the bracket of a tripod of a machine gun.

Another object of my invention is to provide a container wherein the cartridge belt is placed in a rolled condition and means are provided for facilitating the correct and regular feeding of the cartridges to the machine gun.

Another object of my invention is to provide a strip preferably formed of metal on which the cartridge belt is first placed in its unwound or flat condition so that when the cartridge belt is ready to be placed in the container, the strip of metal will, of course, be interspersed between the folds of the cartridge belt.

Another object of my invention is to so form this strip that on one side a metal tooth will extend directly behind the rear face of each cartridge, and on the opposite side of the said strip is formed a series of teeth but so that the nose of each cartridge will lie between the same.

Another object of my invention is to provide a container that may be formed with integral wing clips that may be forced rearwardly when the container is to be fastened to the tripod; or to form a separate bracket that may be used with the container that may be quickly and readily slipped over the bracket arm on the tripod.

Another object of my invention is to provide means for preventing disengagement or loss of a cartridge from the belt, as it is well known that if the trigger of the machine gun comes opposite a blank space it may cause the gun to jam.

With these and other objects in view my invention consists of certain new and novel

constructions and combination of parts as will be hereinafter more fully described and pointed out in the claims.

Referring now to the drawings forming a part hereof Fig. 1 is a side elevation of my improved cartridge belt container with a portion thereof broken away showing the coiled cartridge belt and spacing means contained therein;

Fig. 2 is a fragmentary view of the spacing means showing a portion of the cartridge belt with a few cartridges contained therein;

Fig. 3 is a side elevation showing the container secured to the bracket with the upper portion of said container removed;

Fig. 4 is a top plan view of the container as secured to the bracket, the upper portion thereof removed;

Fig. 5 is a fragmentary view showing one side of the spacing means and the cartridges placed therein;

Fig. 6 shows a modified form of the bracket and container;

Fig. 7 is a top plan view of the bracket the dotted line showing how the same is removed;

Fig. 8 is an end view thereof; and

Fig. 9 is a fragmentary view of one of the arms of bracket but in a reversed position for the sake of clearness.

Referring now to the drawings and to the preferred form shown in Figs. 1 to 5 it will be seen that the container proper consists of a bottom portion 1 and upper portion 2, the bottom portion 1 being slightly reduced at 3 so that the upper portion 2 may fit snugly over the same. The container is preferably round in cross-section and the width of the container is slightly greater than the length of the cartridges 4 which are to be carried in said container. Secured to the lower portion 1 of the said container are metal arms 5 that are bent slightly outwardly as at 6 which arms may be fastened by the rivets 7 or any other preferable means. These arms 5 are preferably made of some flexible metal so that the same may be bent rearwardly to extend in the position shown in Fig. 3.

Formed on the other ends of the arms are the lug portions 8 which are provided for the purpose of engaging the bracket 9 (shown in dotted lines in Figures 3 and 4) on the cradle of the machine gun tripod.

105

110

A strip of metal 10 is secured to the inner edge of the lower portion of container 1 which is adapted to extend into the upper portion 2 of the container when the parts are assembled and which strip 10 is adapted to be folded upwardly and downwardly when the cartridges are to be fed to the machine gun. This strip of metal prevents the gun from "chattering".

10 Referring now to the spacing means as shown in Figs. 1, 2, 3 and 5 it will be seen that a metal strip 11 is used that is slightly greater in width than the ordinary cartridge belt 12 and is preferably formed on a thin 15 flexible strip of metal and having its opposite edges bent upwardly for a slight distance. These edges are then serrated, the serrations on the one edge 13 being so formed that a tooth 14 will come directly behind the 20 rear face 15, of each cartridge. The serrations on the edge 16 are so arranged with regard to cartridges that the nose of the same will fit within the apertures between the teeth 17, so that when the cartridge is placed 25 in the belt and the belt in turn is placed in the spacing means the teeth on one side of the spacing means 11 will come directly behind the rear faces of the cartridges while 30 the nose of the bullet will lie snugly between the teeth 17.

By using this spacing means, when the cartridge belt is fed from the container to the machine gun the distribution of the cartridges will be in an even manner, and 35 the cartridges held tightly in their correct spaced relation and prevented from slipping from the cartridge belt which is greatly desired for if a blank is fed into the gun the same will jam.

40 Referring to the modified form of container and bracket as shown in Figures 6 to 9 inclusive it will be understood that this container 18 is similar in most respects to the container shown in Fig. 1 but in this 45 form a bracket is used having integral arms. This bracket 19 is preferably U shaped in form and has hooked portions 20 formed on the open ends of the arms, which hooked portions are adapted to be slipped over a 50 bracket 21 which is always formed on the machine gun tripod.

A bolt 22 is provided which has a square portion near its head 23 which fits within a square opening 24 formed in one of the arms 55 and the other of said arms is provided with a slotted portion 25 so that the bolt may be quickly removed when desired, and by having the square head fitted within said opening it, of course, is prevented from turning 60 when the container is forced into said bracket.

A strip 26 (Fig. 1) is provided that has a handle 27 at one end, which strip may be attached to both portions of the container so 65 that the halves of said container will not

become separated until desired. If desired, a spacing means may be used in both containers, although in the modified form of the invention the same has been dispensed with.

The metal strip 10 for preventing the 70 chattering of the cartridge belt is provided the same as in the preferable form.

From the foregoing it will be seen that I have provided a simple form of container that may be quickly and readily attached to 75 the bracket of the machine gun tripod and by providing spacing means as heretofore described the cartridges will always be in their correct position in the cartridge belt and will be prevented from being accidentally removed therefrom.

Having thus described my invention what I desire to secure by Letters Patent is:

1. A cartridge container comprising upper and lower sections, arms for supporting the 85 said container, said arms adapted to be placed over a bracket and means secured to the inner surface of the lower portion of said container adapted to be forced outwardly to facilitate the removal of a cartridge belt 90 from said container.

2. A cartridge container comprising upper and lower sections, in combination with bracket arms to support the container, said arms provided with engaging hooks on their 95 outer ends, and adapted to be passed over a bracket on a gun tripod, a metal strap secured to the inner surface of the lower section of said container and adapted to be swung outwardly to facilitate the smooth withdrawing action of a cartridge belt to be carried in said container.

3. A cartridge container comprising two sections and a metal strap secured in one section and adapted to be folded outwardly 105 to provide a rest for a cartridge belt adapted to be carried in said container, arms for supporting said container, the outer ends of said arms having a hooked portion adapted to co-operate with a bracket on a gun tripod. 110

4. A cartridge container comprising upper and lower sections, arms secured to the opposite sides of lower section of said container and spaced from and extending parallel with said sides, the outer ends of said 11 arms formed for detachable engagement with a bracket on a gun tripod for supporting said container.

5. A cartridge container comprising two sections and means secured in one section 12 and adapted to be folded outwardly to provide a rest for a cartridge belt carried in said container.

6. A cartridge container comprising upper and lower sections and means secured to 12 the inner surface of the lower section adapted to be forced outwardly to facilitate the removal of a cartridge belt from said container.

JOHN S. PEOPLES.
